The ornamental design for spectacles, as shown and described.

DESCRIPTION

FIG. 1 is a front perspective of spectacles, showing my new design;

FIG. 2 is a front view thereof;

FIG. 3 is a rear view thereof;

FIG. 4 is a side view thereof;

FIG. 5 is a side view thereof, opposite that of FIG. 4;

FIG. 6 is a top view thereof;

FIG. 7 is a bottom view thereof; and,

FIG. 8 is a rear perspective view showing a portion of the spectacles.

The evenly dashed broken lines illustrate portions of the spectacles that form no part of the claimed design. The unevenly dashed broken lines demarcate the boundary of the portion of the article shown in FIG. 8.
